UNITED STATES PATENT OFFICE.

AUGUST G. LIEBMANN, OF CHICAGO, ILLINOIS.

RAIL-CHAIR.

1,279,726.

Specification of Letters Patent. Patented Sept. 24, 1918.

Application filed January 11, 1916, Serial No. 71,584. Renewed June 13, 1918. Serial No. 239,877.

To all whom it may concern:

Be it known that I, AUGUST G. LIEBMANN, a citizen of the United States, residing at Chicago, in the county of Cook and State 5 of Illinois, have invented certain new and useful Improvements in Rail-Chairs, of which the following is a specification.

This invention relates to railway track appliances and more particularly to rail 10 chairs.

The object of the invention, generally stated, is to provide a chair which will hold the rails under all conditions of track without the use of rail anchors and which will 15 positively prevent creeping of the rails.

A further object of the invention is to provide a rail chair particularly adapted for use on soft wood ties or treated soft wood ties and which will permit of both vertical 20 and lateral adjustment of the rails for surface and gage without disturbing the primary fastening devices and, consequently, materially prolong the effective life of the tie.

25 A further object is to provide a rail chair, the base of which is provided with depending abutments or dowels which extend within the tie and upstanding abutments which co-act with the rail clamping members for 30 holding the rails in different positions of lateral and vertical adjustment.

A further object is to provide the rail clamping members with angular faces which engage the rail and upstanding abutments, 35 respectively.

A further object is to provide means on the upstanding abutments and co-acting 40 with the rail clamping members for guiding said members to their seats and preventing accidental rotation thereof after adjustment.

A further object is to so construct the parts that there shall be no torsional or lateral strain on the bolts or primary fastening devices, thereby making it practical to 45 use bolts of relatively small diameters.

A still further object of the invention is generally to improve this class of devices so as to increase their utility, durability and 50 efficiency, as well as to reduce the cost of manufacture.

Further objects and advantages will appear in the following description, it being understood that various changes in form,

proportions and minor details of construction may be resorted to within the scope of the appended claims. 55

In the drawings:

Figure 1 is a perspective view of a rail chair embodying the present invention; 60

Fig. 2 is a top plan view;

Fig. 3 is a transverse sectional view;

Fig. 4 is a bottom plan view of the base plate;

Fig. 5 is a top plan view of one of the rail clamping members;

Fig. 6 is a side view of said rail clamping member;

Fig. 7 is a bottom plan view;

Fig. 8 is a side elevation of one of the screw caps;

Fig. 9 is a bottom plan view thereof;

Fig. 10 is a side elevation, partly in section, showing the chair used for holding angle bars at the junction of adjacent rails; 75

Fig. 11 is a side elevation of Fig. 10;

Fig. 12 is a top plan view of one of the clamping nuts shown in Fig. 3;

Fig. 13 is a side elevation thereof;

Fig. 14 is a top plan view of a modified form of clamping nut;

Fig. 15 is a side elevation thereof.

Corresponding and like parts are referred to in the following description and indicated in all the views of the drawings by 85 the same reference characters.

Referring to the drawings, A represents a rail having a standard cross section, and B a tie supporting the rail. Mounted upon the cross tie B is a bed plate 5, preferably 90 a malleable casting, although the plate may be otherwise formed, if desired. The bed plate 5 is substantially rectangular in shape and preferably extends the entire width of the upper surface of the tie, as shown. Depending from the bed plate 5 and preferably 95 formed integral therewith are extensions or dowels 6 which fit into correspondingly shaped recesses 7 formed in the upper surface of the cross tie and constitute in effect 100 abutments. The exterior walls of the dowels 6 are preferably smooth and slightly tapered, while the interior walls thereof are cylindrical and also preferably smooth. The upper ends of the dowels open through the 105 upper surface of the bed plate 5, while the lower ends of said dowels are provided with apertures 8 for the reception of primary fas-

tening devices preferably in the form of bolts 9, each comprising a straight shank of square stock or, if desired, a round stock or shank with a square portion upset under 5 the head to engage the hole in the tie and prevent the bolt from turning. The lower end of each primary fastening device or bolt 9 is provided with a head 10 which bears against a washer 11 on the lower surface of 10 the tie, while the upper end of the bolt is preferably conical and provided with threads 12 for engagement with a clamping nut 13. The clamping nut 13 is preferably of the 15 construction illustrated in Figs. 12 and 13 of the drawings, that is to say, the upper face of said nut is provided with notches or 20 depressions 14 to permit the nut to be conveniently grasped with a suitable socket wrench and clamped in engagement with 25 the base of the adjacent dowel, so as to hold the base plate 5 in position on the tie when transporting the ties from the treating plant to the place of use. The clamping nuts 13 also serve to hold the bolts 9 in position to receive the screw caps hereinafter referred to.

Spaced inwardly from the opposite ends of the bed plate 5 are upstanding abutments 15, preferably formed integral with the 30 plate and extending approximately one-half the width thereof, these abutments being arranged at diagonally opposite corners of the bed plate and being connected therewith by terminal substantially triangular webs 16. 35 The abutments 15 are further reinforced and strengthened by a plurality of buttressing webs 17 which extend from the upper ends of the abutments 15 to the adjacent end of the plate, as shown.

40 That portion of the bed plate 5 opposite each upstanding abutment 15 is preferably cut-away at 18 in order to lighten the weight of the plate, while the lower face of said bed plate is formed with a plurality of substantially elliptical depressions 19 arranged 45 in staggered relation throughout the entire area of the plate. These depressions 19 not only lighten the weight of the plate but also form in effect pockets to receive the fiber of the wood of the tie when the bed plate is positioned on the tie and firmly clamped thereto.

As a means for holding the rail A in different positions of lateral and vertical adjustment on the bed plate, there are provided 55 interchangeable rail clamping members 20 each preferably octagonal in shape and provided with a depending eccentric portion 21 having a plurality of angular faces 22 preferably eight in number, as best shown in 60 Figs. 5 to 7 inclusive of the drawings. Each rail clamping member includes a circumferential flange 23 having angular faces 24 corresponding in number to the angular 65 faces of the eccentric 21 and the lower face

of this flange 23 is beveled to form a clamping lip 25 adapted to bear against the base flange of the rail. Arranged on the inner face of each abutment 15 are spaced locking ribs 26 which engage the angular faces 24 of the rail clamping members and serve to prevent accidental rotation of said members after adjustment. Each rail clamping member is preferably provided with a plurality of spaced radiating reinforcing ribs 27, 75 while the upper face of each clamping member, around the opening therein, is preferably flat to form a seat 28 for a spring washer 29.

Extending through the opening or bore 30 in each rail clamping member, is a secondary fastening device preferably in the form of a screw cap 31, cylindrical in form, and provided with a hollow portion or bore, the interior walls of which are threaded at 32 for engagement with the threads 12 on the adjacent primary fastening device or bolt 9. Each screw cap is preferably provided with an angular head 33 by means of which the screw cap may be conveniently grasped with 90 a wrench or other tool and said screw cap rotated to clamp the members 20 in engagement with the rail and also to prevent displacement of the primary fastening devices or bolts 9. It will thus be seen that the 95 screw caps 31 perform the dual function of a locking or clamping means for the rail clamping members 20 and as a permanent clamping means for the bolts 9. It will here be noted that the rail clamping members 20 are disposed in staggered relation on the bed plate 5, while the primary fastening devices or bolts 9 not only serve to hold the bed plate 100 on the cross tie but by engagement with the threaded walls of the screw cap serve to lock the rail clamping members in contact with the base flange of the rail. By reference to Figs. 2 and 3 of the drawings, it will also be noted that the clamping lip 25 of each rail clamping member bears against the base flange of the rail, while the adjacent angular face 22 of the eccentric bears against the adjacent longitudinal edge of the rail and one of the angular faces 24 of the flange 23 bears against the inner face of the adjacent abutment, the rail clamping members being locked against rotation after adjustment by engagement with the locking ribs 26. By such a construction, the rails may be adjusted laterally for gage and vertically for surface without disturbing the primary fastening devices and, consequently, without respiking or otherwise mutilating the tie.

When the rail is adjusted vertically for surface, a shim, indicated at 34, is interposed 115 between the base plate 5 and the lower face of the rail, as best shown in Fig. 3 of the drawings.

In order to adjust the rail laterally on the bed plate for gage, it is merely necessary to 120

remove the screw caps 31 and position one of the rail clamping members on the base plate with the large portion of the eccentric bearing against the base flange of the rail 5 on one side thereof and with the short portion of the eccentric of the other clamping member bearing against the base flange of the rail on the other side of said rail, after which the screw caps are threaded on the 10 bolts 9 and adjusted home, which clamps the members 20 in engagement with the base flange of the rail and effectually prevents accidental displacement of said rail. It will be understood that by moving the rail 15 clamping members 20 to different positions of adjustment, upon the bed plate 5, the rail may be shifted in either direction for gage, as required. In order to adjust the rail vertically for surface, the screw caps are rotated to elevate the same and the shim 34 placed beneath the rail, after which the screw caps are tightened, as best shown in Fig. 3 of the drawings.

Particular attention is called to the fact 25 that when the rail clamping members are adjusted, one of the angular faces of the eccentric 21 of each clamping member will bear against the rail while one of the angular faces of the flange 23 will bear against 30 the adjacent upstanding abutment 15 so that the abutments 15 receive the lateral thrust of the rail and the primary fastening devices or bolts 9 receive no torsional or lateral strain, thereby making it practical to use 35 bolts of relatively small diameter. It will also be noted that the vertical ribs 26 on the abutments not only serve to assist in preventing accidental rotation of the rail clamping members after once adjusted, but 40 also form vertical guides for the rail clamping members and direct said rail clamping members onto the bed plate after said members have been rotated to the proper position to effect the necessary adjustment of the rail. 45 In other words, the ribs 26 form guides for the rail clamping members when adjusting said members vertically for gage and also serve to guide the members onto the bed plate after said members have been rotated 50 to the required distance to effect the necessary lateral adjustment of the rail for gage.

In Figs. 10 and 11 of the drawings, the chair is shown in connection with a rail joint, one of the chairs being supported on 55 each tie and engaging the adjacent angle bars 35. The construction and operation of this form of the chair is similar to that shown in Fig. 1, with the exception that the bed plate 5', shown in Figs. 10 and 11, is 60 made of sufficient length to accommodate the lateral flanges of the angle bars 35. A modified form of clamping nut is shown in Figs. 14 and 15, the nut 13', in this form of the device, being provided with upstanding teeth 36 for engagement with a suitable

wrench, instead of the sockets 14 shown in Figs. 12 and 13. It is obvious that either form of clamp nut may be employed at will. It will also be understood that the rail chairs will be made in rights and lefts but that the 70 parts are so constructed that the rail clamping members may be interchanged, when desired.

From the foregoing description, it will be seen that the improved chair effectually 75 eliminates the use of rail anchors, positively prevents creeping of the rails and provides for gage variations on curves and tangents; for restoration of gage without respiking and for rail surface variations and the like 80 without respiking. The chair and fastener forming a part thereof are so constructed that it will effectually eliminate mechanical wear to cross ties and, consequently, prolong the life of treated or untreated ties by providing for lateral and vertical adjustment of the chair for curves or tangents without the necessity of disturbing the primary fastening devices or respiking or shifting the bed plate of the chair on the tie to effect such 85 90 adjustments.

Having thus described the invention, what is claimed as new is:

1. A rail chair including a bed plate having upstanding abutments, primary fastening devices for the bed plate, rail clamping members movable to different positions of adjustment on the bed plate and engaging the abutments, and secondary fastening devices 95 100 and co-acting with the rail clamping members.

2. A rail chair including a bed plate having upstanding abutments, primary fastening devices for the bed plate, rail clamping members movable to different positions of adjustment on the bed plate and engaging the abutments, means carried by the abutments and co-acting with the rail clamping members for guiding said members to their 105 110 seats, and secondary fastening devices engaging the primary fastening devices for holding the clamping members in adjusted position.

3. A rail chair including a bed plate having upstanding abutments, primary fastening devices for the bed plate, rail clamping members movable to different positions of adjustment on the bed plate and engaging the abutments, spaced ribs on the abutments 115 120 for guiding the rail clamping members to their seats, and secondary fastening devices engaging the primary fastening devices and co-acting with the rail clamping members.

4. A rail chair including a bed plate having upstanding abutments disposed in staggered relation, primary fastening devices for said bed plate, rail clamping members movable to different positions of adjustment 125 on the bed plate and engaging the abut-

- ments, and secondary fastening devices extending through the rail clamping members and engaging the primary fastening devices. 65
5. A rail chair including a bed plate having depending abutments and upstanding abutments, primary fastening devices extending through the depending abutments, rail clamping members movable to different 70 positions of adjustment on the bed plate and engaging the upstanding abutments, and secondary fastening devices engaging the primary fastening devices and co-acting with the rail clamping members.
10. A rail chair including a bed plate having upstanding abutments, primary fastening devices for the bed plate, rail clamping members having angular faces for engagement with a rail and the abutments, respectively, means on the abutments for 75 guiding the rail clamping members to their seats, and secondary fastening devices engaging the primary fastening devices and co-acting with the rail clamping members. 80
15. A rail chair including a bed plate having depending abutments and upstanding abutments, primary fastening devices extending through the depending abutments, rail clamping members movable to different 85 positions of adjustment on the bed plate and engaging the upstanding abutments, ribs formed on said upstanding abutments for guiding the clamping members to their seats, and secondary fastening devices engaging the primary fastening devices and co-acting with the rail clamping members. 90
20. A rail chair including a bed plate having upstanding abutments, primary fastening devices for the bed plate, rail clamping members movable to different positions of adjustment on the bed plate and provided with depending eccentrics having angular faces for engagement with a rail, said rail clamping members having other angular faces for engagement with the abutments, and secondary fastening devices extending through the rail clamping members and engaging the primary fastening devices. 95
25. A rail chair including a bed plate having upstanding abutments and depending abutments, the lower face of the bed plate being provided with depressions, primary fastening devices extending through the depending abutments, rail clamping members movable to different positions of adjustment on the bed plate and engaging the upstanding abutments, means on said upstanding abutments for guiding the rail clamping members to their seats, and secondary fastening devices engaging the primary fastening devices and co-acting with the rail clamping members. 100
30. A rail chair including a bed plate having upstanding abutments disposed in staggered relation, buttressing webs connecting the outer faces of the abutments with the base plate, primary fastening devices for the bed plate, rail clamping members movable to different positions of adjustment on the bed plate and engaging the abutments, ribs formed on the inner faces of the abutments for guiding the clamping members to their seats, and secondary fastening devices engaging the primary fastening devices and co-acting with the rail clamping members. 105
35. A rail chair including a bed plate having upstanding abutments disposed in staggered relation, each abutment having its inner face connected with the bed plate by terminal reinforcing webs and its outer face connected to said bed plate by intermediate buttressing webs, primary fastening devices for the bed plate, rail clamping members movable to different positions of adjustment on the bed plate and engaging the abutments, spaced ribs formed on the inner faces 110
40. A rail chair including a bed plate having upstanding abutments disposed in staggered relation, each abutment having its inner face connected with the bed plate by terminal reinforcing webs and its outer face connected to said bed plate by intermediate buttressing webs, primary fastening devices for the bed plate, rail clamping members movable to different positions of adjustment on the bed plate and each having a flange provided with an angular face for engagement with the adjacent abutment and a depending eccentric having angular faces for engagement with a rail, and secondary fastening devices extending through the rail clamping members and engaging the primary fastening devices. 115
45. A rail chair including a bed plate having upstanding abutments, primary fastening devices for the bed plate, rail clamping members movable to different positions of adjustment on the bed plate and each having a flange provided with an angular face for engagement with the adjacent abutment and a depending eccentric having angular faces for engagement with a rail, and secondary fastening devices extending through the rail clamping members and engaging the primary fastening devices. 120
50. A rail chair including a bed plate having depending abutments for insertion in a cross tie and provided with upstanding abutments, primary fastening devices extending through the tie and depending abutments, rail clamping members movable to different positions of adjustment on the bed plate and each having a flange provided with angular faces for engagement with the adjacent upstanding abutment and a depending eccentric having angular faces for 125

engagement with the base flange of a rail, and secondary fastening devices extending through the rail clamping members and engaging the primary fastening devices.

5 15. A rail chair including a bed plate having depending abutments and upstanding abutments, the latter being spaced inwardly from the opposite ends of the bed plate and disposed in staggered relation, 10 primary fastening devices for securing the bed plate on a cross tie, rail clamping members movable to different positions of adjustment on the bed plate and each provided with a flange having angular faces for engagement with the adjacent abutment, and a depending eccentric having angular faces for engagement with the base flange of a rail, ribs formed on the inner faces of the abutments for guiding the rail clamping 15 members to their seats, and secondary fastening devices extending through the rail clamping members and engaging the primary fastening devices.

16. A rail chair including a bed plate 25 having upstanding abutments, primary fastening devices for securing the bed plate to a cross tie, rail clamping members movable to different positions of adjustment on the bed plate for holding a rail in lateral and 30 vertical adjustment with respect to the bed plate, means carried by the abutments for guiding the rail clamping members to their seats, and secondary fastening devices engaging the primary fastening devices and 35 said rail clamping members.

17. The combination with a cross tie, of a bed plate seated on the cross tie and provided with spaced upstanding abutments, a rail adapted to rest on the bed plate or on a 40 shim, primary fastening devices engaging the cross tie, rail clamping members movable to different positions of adjustment with respect to the bed plate and engaging the abutments, and secondary fastening 45 devices engaging the primary fastening devices and co-acting with the rail clamping members for holding the rail on said bed plate or shim.

18. The combination with a cross tie having spaced recesses formed therein, of a bed plate resting on the cross tie and provided with spaced depending abutments fitting within the recesses and also provided with upstanding abutments, primary fastening 55 devices extending through the tie and de-

pending abutments, a rail adapted to rest on the bed plate or on a shim, rail clamping members movable to different positions of adjustment on the bed plate and engaging the upstanding abutments, means on the upstanding abutments for guiding the rail clamping members to their seats, and secondary fastening devices engaging the primary fastening devices and co-acting with the rail clamping members for holding the 60 rail on said bed plate or shim.

19. A rail chair including a bed plate having an upstanding abutment, a primary fastening device for the bed plate, a rail clamping member movable to different positions 70 of adjustment on the bed plate and engaging the abutment, and a secondary fastening device engaging the primary fastening device and co-acting with the rail clamping member.

20. A rail chair including a bed plate having a depending abutment and an upstanding abutment, a primary fastening device extending through the depending abutment, a rail clamping member movable to different 80 positions of adjustment on the bed plate and engaging the upstanding abutment, and a secondary fastening device engaging the primary fastening device and co-acting with the rail clamping member.

21. A rail chair including a bed plate having an upstanding abutment, a primary fastening device for the bed plate, a rail clamping member bearing against the abutment and having a portion adapted to engage 90 over the upper surface of the base flange of a rail and another portion adapted to bear against the adjacent longitudinal edge of the base flange of said rail, and a secondary fastening device engaging the primary 95 fastening device and co-acting with the rail clamping member.

22. A rail clamping member comprising a body having an opening therethrough for the reception of a fastening device and provided with a circumferential flange, the lower face of which is inclined downwardly and the marginal edge thereof formed with a series of angular faces, said body being provided with a depending eccentric portion and the upper surface of the flange being formed with reinforcing ribs radiating from the opening in the body.

In testimony whereof I affix my signature.

AUGUST G. LIEBMANN. [L.S.]
